UNITED STATES PATENT OFFICE

EDWARD WUENN, OF CHICAGO, ILLINOIS, ASSIGNOR TO RADIO CABINET MANUFACTURING CORPORATION, A CORPORATION OF ILLINOIS

DESIGN FOR A RADIOCABINET

Application filed August 6, 1930. Serial No. 36,573. Term of patent 3½ years.

To all whom it may concern:

Be it known that I, EDWARD WUENN, a citizen of the United States, residing at Chicago, in the county of Cook and State of Illinois, have invented a new, original, and ornamental Design for Radiocabinets, of which the following is a specification, reference being had to the accompanying drawing, forming part thereof, in which a perspective view of the cabinet is shown.

I claim:

The ornamental design for a radio cabinet as shown.

In testimony whereof I affix my signature at Chicago, Illinois.

EDWARD WUENN.
